(57) **CLAIM**

The ornamental design for a wrench body, as shown and described.

DESCRIPTION

FIG. 1 is a top side perspective view of a wrench body. FIG. 2 is a first side view of the wrench body of FIG. 1. FIG. 3 is a second side view of the wrench body of FIG. 1. FIG. 4 is a top plan view of the wrench body of FIG. 1. FIG. 5 is a bottom plan view of the wrench body of FIG. 1. FIG. 6 is a first end view of the wrench body of FIG. 1. FIG. 7 is a second end view of the wrench body of FIG. 1; and, FIG. 8 is a detailed partial perspective view of the second end of the wrench body of FIG. 1.

The broken lines shown are included for the purpose of illustrating portions of the wrench body that form no part of the claim.

1 Claim, 8 Drawing Sheets
